SINTERING APPARATUS

Alfred W. Babb, Cleveland, Ohio

Application August 28, 1943, Serial No. 500,388

1 Claim. (Cl. 266—21)

1

This invention relates generally to the art of sintering and particularly to a new and improved method of, and to new and improved apparatus for, sintering by which the sizes of the pieces of sintered material may be controlled.

Fine materials, such as iron ore, flue dust and the like have been sintered heretofore by the steps of mixing them with fine, combustible material such as coal, coke and the like, charging the mixture onto pallets of a sintering machine, igniting the combustible material, and drawing air therethru until the combustible material was more or less completely burned. Then the highly heated and usually still burning sinter was discharged from the pallets. Frequently this sinter was then cooled by spraying water onto it.

Since the temperature attained by the burning part of the charge is as much as about 1000° F. and since the burning progresses down from the top surface of the charge, the temperature of the entire charge is still quite high when combustion is practically completed, the upper layers being somewhat cooler than the lowest layer.

The effect of suddenly cooling the hot sinter with water was that the sintered clusters are disintegrated and in many instances as much as 90% of the sintered material was less than about 1" in size. I believe that when water came into contact with the sinter which was highly heated, for example, at about 1000° F. or even at lower temperatures down to about 250° F., the friable, porous sinter was broken, thus accounting for the high percentage of small sized particles in the water-quenched product. While such small sized material is suitable for charging into blast furnaces, it is not desirable for charging into open hearth furnaces where a much larger percentage of the material should be 1" or larger in size.

I have discovered that when hot sintered material is cooled on the pallets by the passage of air therethru, the amount of pieces larger than about 1" in size may be greatly increased; as much as 70% or more of the sintered product being larger than 1" in size. I have also discovered that by controlling the amount and/or pressure of air which is used for cooling the hot sinter, it is possible not only to control the size of the cooled particles but also to obtain stronger particles and thus adapt the product to various intended uses. I believe that the particles are strong because they are cooled thru the temperature in which they have little strength without weakening them and when this cooling

2

is completed they possess an unweakened structure which is quite strong.

The method of the present invention, briefly stated, comprises the steps of charging a mixture of fine material to be sintered and fine combustible material onto a pallet of a sintering machine, igniting and burning substantially all the combustible material in the mixture, then drawing air thru the highly heated sinter and reducing its temperature, and then discharging the thus cooled material from the pallet. The apparatus embodying the present invention may be briefly described as comprising a sintering machine having pallets, means to charge onto the pallets a mixture of fine material to be sintered and fine combustible material, means to ignite the mixture, means to draw air thru the burning mixture and means to draw air thru the resulting sinter to cool the same before it is discharged from the pallets, and means for regulating the amount of air which is drawn thru the sintered material.

In the drawings accompanying and forming a part of this specification,

25 Figure 1 is a diagrammatic, side elevational view, illustrating one form of apparatus embodying the present invention; and

Figure 2 is a view showing a modification of the suction apparatus of Fig. 1.

30 Fig. 1 shows a sintering machine of the Dwight & Lloyd endless track type. This machine comprises a plurality of pallets 1 which are movable around a closed path defined by rails or track 1a which support and guide the pallets. A charging hopper 2 is disposed above the pallets at one end of the track to load charges of finely divided combustible material and material to be sintered onto the pallets 1 as they pass therebeneath. An ignition furnace 3 of suitable form

40 is provided adjacent to the hopper 2 to ignite the combustible material in the mixture on the pallets as they come therebeneath. A plurality of the usual suction boxes 4 is disposed beneath the pallets and with their open tops closely adjacent to the under sides of the pallets. These suction boxes 4 extend for the full width of the pallets and extend along the tracks for a distance substantially equal to the distance thru which the pallets travel while substantially all the combustible material in the mixture is burning. These boxes 4 are connected to a manifold 5 from which a pipe 6 leads to a suction fan 7 which serves to withdraw air thru the burning charge on the pallets and to discharge such air into a stack 8.

The tracks 1a of the sintering machine are extended so that the pallets containing hot sintered material will travel some distance therealong after combustion ceases and before the sinter is discharged from the pallets and into a discharge chute 8. Beneath the pallets, in this extended portion of the tracks are disposed a plurality of suction boxes 10 which are similar to boxes 4 and which are connected to manifold 11. This manifold communicates thru pipe 12 with a suction fan 13 which serves to draw air thru the burned sinter above boxes 10 and discharge such air into stack 8. It will be noted that the suction boxes 10 correspond to, and are similar to, the boxes 4 and that the four boxes 10 here illustrated extend along the machine tracks a distance equal to the combined length of twelve pallets 1. It will be understood that more or less than four suction boxes 10 may be employed, depending on the result desired, particularly the extent of cooling of the sinter, for the more boxes 10 that are provided the more air will pass thru the burnt sinter and the lower will be the temperature of the sinter when it reaches the discharge end of the machine.

It will be understood that the amounts of air drawn thru the pallets by fans 7 and 13 may be regulated by controlling the sizes and speeds of these fans. For example, the amount of air drawn thru the pallets above suction boxes 10 may be varied from zero when fan 13 is not operating, to the full capacity of the fan, when it is operating at maximum speed. Furthermore, the speed of these two fans may be regulated independently of, or in accordance with, the speed of the other fan.

In Fig. 2 the manifold 5 is connected to a suction fan 15 by a conduit 16 containing a flow-regulating valve 17. A relief valve 18 opens into conduit 16 on the fan side of valve 17. The fan 15 withdraws air from manifold 5 and delivers it into stack 19. The conduit 20 leading from manifold 11 is provided with a similar flow-regulating valve 21 and a similar relief valve 22 and opens into pipe 16 between the valve 17 thereof and fan 15. By adjusting the valves 17 and 22 the amounts of air passing thru suction boxes (similar to boxes 4 and 10 of Fig. 1) connected to manifolds 5 and 11 may be controlled, the relief valves 18 and 21 serving to admit air into the respective pipes 16 and 20 to relieve the amount of vacuum in either line.

Altho the sintering machine illustrated in Fig. 1 is of the endless track type, it will be understood that the present invention is not confined to such a machine but may be employed with sintering machines of other types, for example, the Greenawalt type. One important difference between the prior machines and a machine em-

bodying the present invention is that cooling air is drawn thru a highly heated charge on a pallet after substantially all the combustible material in the charge has been burned and that such air reduces the temperature of the sinter from about 1000° F. to a temperature of for example about 250° F. before the sinter is discharged from the pallets.

If desired, manifold 5 of Fig. 1 may be replaced by two separate manifolds similar to, but only about half the length of, that manifold and connecting each such manifold to the fan 7 by a conduit similar to the conduit 16 or 20 of Fig. 2.

Having thus described the invention so that others skilled in the art may be able to understand and practice the same, I state that what I desire to secure by Letters Patent is defined in what is claimed.

What is claimed is:

20 In a sintering machine having an endless track, pallets to run on said track, means to ignite combustible material in an ore charge on said pallets, and means to draw air thru a burning charge on a moving pallet and including suction boxes, a manifold, a conduit having a flow regulating valve, a relief valve and a fan operatively connected together, the combination of a cooling zone along the track for pallets whose charges have been burned, and means for drawing cool air thru burned charges on pallets in said cooling zone, said last named means including a plurality of suction boxes, a manifold connected to the boxes, and a conduit having a flow regulating valve and a relief valve and connecting said last named manifold to the afore-said fan.
